UNITED STATES PATENT OFFICE.

CEARNEL MITCH BLACKBURN, OF CAVENDISH, IDAHO, ASSIGNOR OF ONE-THIRD TO
L. G. PETERSON, OF KENDRICK, IDAHO.

DRAG WOOD-SAWING MACHINE.

1,263,025.

Specification of Letters Patent. Patented Apr. 16, 1918.

Application filed April 9, 1917. Serial No. 160,870.

To all whom it may concern:

Be it known that I, CEARNEL MITCH BLACKBURN, a citizen of the United States, residing at Cavendish, in the county of 5 Clearwater and State of Idaho, have invented certain new and useful Improvements in Drag Wood-Sawing Machines, of which the following is a specification.

My invention relates to drag wood-sawing 10 machines.

An important object of the invention is to provide a machine of the above mentioned character, having means to secure the same to the log to be cut, for holding the log 15 against movement, in a secure manner.

A further object of the invention is to provide means of the above mentioned character, which is simple in construction, and may be operated in a highly convenient and 20 expeditious manner.

A further object of the invention is to provide means whereby the machine may be conveniently shifted or moved longitudinally of the log, from one cut to the other.

25 Other objects and advantages of the invention will be apparent during the course of the following description.

In the accompanying drawings forming a part of this specification and in which like 30 numerals are employed to designate like parts throughout the same,

Figure 1 is a side elevation of a machine embodying my invention,

Fig. 2 is an end elevation of the same, and, 35 Fig. 3 is a detail section taken on line 3—3 of Fig. 1.

In the drawings, wherein for the purpose of illustration is shown a preferred embodiment of my invention, the numeral 5 designates a supporting frame, comprising spaced longitudinal beams 6, provided at their forward ends with depending spikes or holding elements 7, adapted to penetrate the upper side of the log 8, to be cut.

45 Extending transversely of the beams 6 is a rock-shaft 9, journaled in bearings 10, rigidly attached to the forward end of the beams 6. Rigidly connected with the rock-shaft 9, near one end thereof, is a lever 11, 50 operating in proximity to a stationary quadrant 12, and equipped with latch means 13, to coact therewith, whereby the lever may be locked in the desired angular position.

Rigidly connected with the rock-shaft 9 55 at a point preferably equidistantly spaced

from the ends thereof, is a crank 14, provided in its upper portion with a slot 15, receiving an arm 16, pivoted within the slot, by means of a transverse pin 17 or the like. The pin is adapted to be inserted in a 60 selected aperture 17', which is spaced and extends longitudinally of the arm 16. The arm 16 is provided at its lower end with a holding dog 18', coacting with the prongs 7, which constitute holding means to engage 65 the log.

Rigidly secured to the upper end of the crank 14 are arms 18, having horizontal extensions 19, which carry a pin or pivot element 20, upon which is pivoted a roller or 70 wheel 21. This roller or wheel is adapted to be swung downwardly for contact with the log 8, for a purpose to be described.

Arranged upon the rear portion of the frame 5 is a prime mover, such as an internal combustion engine 22, driving a pulley 23, engaged by a belt 24, which drives a pulley 25. The pulley 25 serves to rotate a crank 26, having connection with a pitman 27, suitably connected with a saw 28, such 80 as a cross-cut saw. This saw engages with the log and cuts the same, as is obvious.

The operation of the apparatus is as follows:

The forward end of the frame 5 is placed 85 upon the log 8, and the teeth or prongs 7 engage with the upper side of the log. The dog 18' engages upon the opposite side of the log, and by swinging the lever 11 rearwardly, the dog may be elevated with respect to the log, and the coacting dog and prongs 7 formed into the log for a desired 90 distance, to effect a proper holding action between the frame and log. The engine is now started and the saw placed upon the 95 upper side of the log. The saw 28 is reciprocated as is obvious, and the log is cut transversely.

After this action, the saw may be removed from engagement with the log and the lever 100 11 swung forwardly which will first serve to release the dog 18' from holding engagement with the log and subsequently bring the roller 21 into contact with the upper side of the log. Upon further swinging movement of the lever in the same direction, the forward end of the frame 5 may be elevated, thus effecting a disengagement between the prongs 7 and the log, while the roller 21 105 supports the forward end of the frame. The 110

forward end of the frame may now be moved longitudinally of the log, by the roller 21 contacting therewith.

It is to be understood that the form of my invention herewith shown and described is to be taken as a preferred example of the same, and that various changes in the shape, size, and arrangement of parts may be resorted to without departing from the spirit 10 of the invention or the scope of the subjoined claims.

Having thus described my invention, I claim:

1. In a machine of the character described, 15 a frame having one end thereof adapted to be arranged near a log and provided with log engaging means; hoisting mechanism to elevate the said end of the frame to move the log engaging means out of engagement with the log, said mechanism including a rolling element to travel longitudinally of the log; a saw to cut the log; and a prime mover arranged upon the frame and having connection with the saw to operate it.
2. In a machine of the character described, 25 a frame, a rock-shaft connected therewith and extending transversely thereof, a crank rigidly secured to the rock-shaft and adapted for movement toward and away from the log to be cut, a roller pivoted to the crank

to contact with the log, means to turn the rock-shaft, log engaging means secured to the frame, a prime mover arranged upon the frame, a saw to cut the log transversely, and driving connecting means between the saw 35 and prime mover.

3. In a machine of the character described, a frame provided near one end with log engaging means; a rock-shaft secured to the frame and extending transversely thereof, 40 means to turn the rock-shaft and lock the same in adjustment at different positions, a crank rigidly secured to the rock-shaft and extending above the same, an arm pivoted to the crank and depending therefrom and 45 provided near its lower end with a dog, a roll pivotally connected with the crank and adapted to be moved downwardly for contact with the log, a saw to cut the log transversely, a prime mover arranged upon 50 the frame, and driving connecting means between the saw and prime mover.

Signed at Kendrick, in the county of Latah, and State of Idaho, this 22nd day of March, 1917.

CEARNEL MITCH BLACKBURN.
